OSCAR WIEDERHOLD, OF JERSEY CITY, NEW JERSEY.

INCANDESCENT FUEL-LAMP.

1,187,589.

Specification of Letters Patent. Patented June 20, 1916.

Application filed January 9, 1915. Serial No. 1,265.

To all whom it may concern:

Be it known that I, OSCAR WIEDERHOLD, a citizen of the United States, and a resident of Jersey City, county of Hudson, State of New Jersey, have invented certain new and useful Improvements in Incandescent Fuel-Lamps, of which the following is a specification.

My invention relates to incandescent fuel lamps and has for its object to provide a lamp of this type having a maximum of efficiency and capable of being advantageously used with illuminating gas as well as with kerosene or other relatively inexpensive and readily available liquid fuel.

My improvement further contemplates constructing the lamp in such a manner as to prevent flickering of the light and spluttering of unvaporized liquid fuel when used or other unintentional spreading thereof under any condition and to thus reduce the danger of fire and explosion to a minimum particularly in lamps utilizing liquid fuel as an operating medium.

Another object of my invention is to provide for a uniform, simple and substantially constant vaporization of the liquid fuel while lamps of the latter type are in operation.

My improvement will be fully described hereinafter and the features of novelty will be pointed out in the appended claims.

Reference is to be had to the accompanying drawings which illustrate an example of my improved construction and in which—

Figure 1 is a side elevation of a vapor lamp partly in section; Fig. 2 is a plan view thereof; Fig. 3 is a horizontal section on the line 3—3 of Fig. 1; Fig. 4 is a similar view on the line 4—4 of Fig. 1; Fig. 5 is a similar view on the line 5—5 of Fig. 1 looking upward with the mantle removed; Fig. 6 is a detail sectional view of a mantle locking device forming part of my arrangement; Fig. 7 is an elevation partly in section of another form of my improvement; Fig. 8 is a similar detail view of still another form thereof; Figs. 9 and 10 are horizontal sections on an enlarged scale taken respectively on the lines 9—9 and 10—10 of Fig. 8 and Fig. 11 is a detail view of another form of air intake arrangement.

As shown in Fig. 1 of the drawings the lamp comprises a receptacle 1 which may form the base of the lamp or be otherwise

arranged and which is adapted to contain liquid fuel such as kerosene or the like under pressure, any convenient means as for instance a pump 2 of any suitable type being connected with said receptacle whereby air is compressed therein and the desired degree of pressure on the fuel is maintained. Any convenient type of escape valve 3 may be provided on said receptacle 1 for permitting air to escape therefrom when it is desired to reduce the pressure and to restrict the feed of the fuel. In the illustrated example a tube 4 communicating with the interior of the receptacle 1 extends upwardly therefrom and is formed at its exit end with a nozzle opening 4^a and further is provided at an intermediate point with a valve chamber 5 and valve 6 of any suitable construction whereby the feed of the fuel through said tube 4 to the burner is controlled. In the assembled condition of the parts the upper portion of the tube 4 extends into a sleeve 7 which depends from an approximately central point of a transverse air inlet tube 8, the free end of the tube 4 at which the nozzle opening 4^a is located being in this manner brought into communication with said air inlet tube 8 as shown in Fig. 1. A mixing tube 9 communicates with said air inlet tube 8 and extends upwardly therefrom in axial alinement with the sleeve 7 and consequently with the tube 4 when the lamp is in its operative condition. Both the sleeve 7 and mixing tube 9 are preferably detachably connected with said air inlet tube 8 in any desired manner as for instance by screw threading. The mixing tube 9 and the sleeve 7 are surrounded by an open ended outer tube 10 of relatively larger diameter and provided with suitable apertures through which the air inlet tube 8 projects in opposite directions, the said outer tube 10 extending upwardly beyond the mixing tube 9 and having its lower end located at a slight distance above the depending end of the sleeve 7 as shown in Fig. 1. The said depending end of said sleeve 7 is preferably screwthreaded to detachably receive a ring 11 having perforations 12 and adapted to fit within and cover the lower end of said outer tube 10, a downwardly flaring deflector 13 depending from said ring 11 and surrounding the tube 4 in the assembled condition of the parts. The upper end of the outer tube 10 is closed by means of a removable cap 14.

having a preferably cone shaped projection 15 projecting downwardly from its inner surface in axial alinement with the mixing tube 9 and surrounded by an annular downwardly converging deflecting surface 16 as clearly shown in Figs. 1 and 6. A mantle support 17 is located on the outer tube 10 at a point preferably just below the air-inlet tube 8 and is provided with bayonet slots 18 10 adapted to receive the projections 19 of a mantle ring 20 from which the mantle 21 is suspended in the usual way. The said mantle is of the inverted type and is provided with an aperture 21^a through which the tube 4 extends so that in the operative position of the parts, the mantle 21 surrounds a portion of the said tube 4 and the deflector 13 and ring 11 and extends below the two last named elements as shown in Fig. 1.

20 In the preferred construction the mantle support is provided with a vertically movable latch 22 operated by gravity and arranged in its operative position to extend across a horizontal portion of one of the bayonet slots 18 to close the same as shown in Fig. 6 and thus prevent a rotation of the ring 20 relatively to the support 17 and an accidental or unintentional dislocation of the mantle 21. Any suitable provision may 30 be made for preventing the said latch 22 from dropping entirely out of the aperture of the mantle support 17 in which it operates as by providing said latch at its opposite ends with enlargements 23. An open ended 35 tubular shell 24 surrounds the mixing tube 9 and is provided with suitable apertures in which the opposite ends of the air inlet tube 8 are secured, so that said tube 8 forms a support for the said shell and the ends of 40 said tube 8 are open therethrough to the atmosphere. Arms 25 depend from said shell 24 and have their lower ends bent inwardly toward each other and secured to a tubular member 26 which is thus supported at a distance 45 beneath and in axial alinement with the sleeve 7 and forms a support for a dish 27 containing asbestos or other fire-proof fibrous material 28 adapted to be saturated with alcohol or the like and ignited to pre- 50 heat the fuel when the lamp is to be used. The tubular member 26 has an internal diameter adapted to slidably fit on the tube 4 and in the operative condition of the lamp preferably rests upon a coil spring 29 sur- 55 rounding the said tube 4 and in turn abutting against the valve chamber 5 of the valve 6 as shown in Fig. 1. With this arrangement it will be seen that the sleeve 7, air inlet tube 8, mixing tube 9, outer tube 10, ring 11, deflector 13, cap 14, mantle support 17, mantle ring 20, mantle 21, shell 24, tubular member 26 and dish 27 are combined in the form of a unit and are adapted to be manipulated as such.

65 When the mantle 21 is to be combined with

the lamp the shell 24 with its connected parts is simply lifted and removed from the lamp after which the said shell is inverted to bring the mantle support 17 into a position in which it is readily accessible. In this inverted position the latch 22 drops down by gravity thereby freeing the coöperating bayonet slot 18 and making it possible to readily introduce the mantle ring 20 into said support 17 and rotate it relatively thereto to position the projections 19 in the horizontal portions of said bayonet slots 18 as shown in Fig. 6 and properly connect the mantle 21 in operative position. In this position the aperture 21^a of the mantle is substantially in axial alinement with the deflector 13, sleeve 7 and tubular member 26. The shell 24 is now reversed back to its normal upright position in which the latch 22 drops back by gravity across the horizontal portion of the coöperating bayonet slot 18 and thus locks the mantle ring 20 against rotation on the support 17 and the mantle 21 in its operative position. The parts may now again be operatively combined with the lamp by placing the tubular member 26 over the end of the tube 4 and sliding it lengthwise thereof until the spring 29 is reached, the tube 4 meanwhile having passed through the aperture 21^a of the mantle 21 and into the combined deflector 13 and sleeve 7 as will be clearly apparent. During the removal of the parts and the replacing thereof as described the tubular member 26 acts as a guide along the tube 4 and maintains the aperture 21^a of the 100 mantle 21 in proper alinement with said tube 4 whereby injury to the mantle 21 by said tube 4 is prevented, this being particularly true when the parts are replaced as set forth. The spring 29 serves to absorb any 105 shock which may result from the replacing of the parts and prevents injury to the mantle and other parts from such cause. This spring may in some cases be omitted or replaced by other devices for accomplishing 110 the same results.

In the operative condition of the lamp the receptacle 1 contains a suitable amount of liquid fuel such as kerosene or the like, it being understood that the pump 2 has been 115 actuated to produce the desired degree of pressure in said receptacle, a suitable gage being included in the structure if desired to indicate said degree of pressure. When it is intended to use the lamp the asbestos 28 or other fibrous material is first saturated with alcohol or the like and ignited whereby the adjacent portion of the tube 4 is preheated. When a sufficient amount of preheating has taken place the valve 6 is opened so that fuel 120 immediately begins to rise in said tube 4 owing to the air pressure in the receptacle 1 and on reaching the preheated portion of said tube 4 is vaporized and in this condition 125 passes from the nozzle 4^a of the tube 4 into 130

the mixing tube 9. In passing to the said mixing tube 9 air is sucked in through the air inlet tube 8 and becomes mixed with the vaporized fuel in said tube 9. This mixture 5 of fuel and air passes from the upper end of the tube 9 into contact with the conical projection 15 and deflecting surface 16 and is deflected downwardly thereby into the annular space between the mixing tube 9 and 10 outer tube 10 as indicated by the arrows in Fig. 1, along which said mixture travels and from which it passes through the perforations 12 into engagement with the deflector 13. From the deflector 13 the mixture of 15 vaporized fuel and air passes into contact with the mantle 21 which is now ignited, it being understood that the deflector 13 gives the current of vaporized fuel and air an upward direction and a whirling motion so that 20 direct contact with any one portion of the mantle is avoided and at the same time the hot mixture is deflected away from the tube 4 so that the latter is prevented from becoming too hot. After the alcohol or the 25 like with which the asbestos or other material is saturated has burned itself out and the mantle has been ignited the tube 4 will be maintained in a heated condition to properly vaporize the fuel rising therein by the 30 heat of the burning vaporized fuel at the mantle. It will be noted that the mixture of vaporized fuel and air first travels upward in the mixing tube 9 and then downward along the same to the mantle and in 35 this way is subjected to a double heating, the consequence of which is that the mixture is brought to a high state of efficiency before it reaches the mantle with the result that perfect combustion and a maximum degree of 40 illumination is secured. The fuel in the receptacle may be maintained under the desired pressure by periodically actuating the pump 2 or if a light of lesser intensity is desired the pressure may be relieved by opening 45 the escape valve 3, the supply of fuel to be vaporized being in this manner reduced.

Instead of using fluid fuel and vaporizing same to operate the lamp ordinary illuminating gas or other gaseous fuel may be used 50 for this purpose in which case the fuel tube 4, instead of communicating with the receptacle 1 would be connected with a gas main or other source of supply. When using gas or similar fuel as suggested the preheating pan 27 may be omitted from the structure if 55 desired the operation of the lamp otherwise being the same as described heretofore. In either case in order to prevent a roaring sound in the lamp caused by the air rushing 60 into and through the air inlet tube 8 any suitable means may be employed. For instance, as shown, tubular members 30 having interior surfaces which converge or taper toward the interior of the tube 8 may be secured in one or both ends thereof and may

be utilized to secure the ends of the air inlet tube 8 in the shell 24, or said tube 8 may be provided interiorly with one or a series of baffle members 31 as shown in Fig. 1. In some cases the members 30 or the members 70 31 alone may be included in the arrangement while in other instances a combination of both may be found desirable. If desired suspending means 32 of any type may be combined with the lamp for supporting a 75 globe of any proper coöperating construction or shape.

In Fig. 7 I have shown my improvement arranged for use in connection with an upright mantle instead of an inverted mantle 80 as in the first form. In this latter form the mantle 21^b which may be of the usual upright type is connected at its upper end with the fuel tube 4 in any suitable manner so as to surround same and be suspended thereon 85 and at its lower end extends over a tube 10^a which surrounds a sleeve 7^a at a distance and forms therewith a chamber 10^b the lower end of which is closed and the upper end of which is covered by means of a ring 11^a having perforations 12^a. In the arrangement 90 being described the fuel tube 4 extends through the sleeve 7^a and mantle 21^b and has its upper end at which the nozzle opening 4^a is located detachably connected with an air inlet tube 8^a as shown in Fig. 7. This air inlet tube 8^a is connected with a mixing tube 9^a and extends in opposite directions therefrom, said mixing tube 9^a projecting 95 upwardly from said air inlet tube and being formed with a return bend so as to extend downwardly and substantially parallel with the fuel tube 4 through a sleeve 8^b which closes the one end of said air inlet tube 8^a and serves to increase the rigidity of structure. The depending free end of the mixing tube 9^a is preferably slightly tapered to detachably fit into a similarly formed socket 9^b forming part of and communicating with a tube 9^c which in turn is connected with the 100 chamber 10^b and preferably comprises an integral part of the sleeve 7^a. A rod or stem 9^d extends downwardly from the tube 9^c and is constructed with a shoulder adapted to rest upon a bracket 5^a extending from 115 a valve chamber 5^b similar to the valve chamber 5 of Fig. 1 and further has a reduced screw threaded end arranged to project through said bracket and accommodate a nut 5^c whereby said tube 9^c and its constituent parts are supported and secured in operative position. A suitable valve 5^d cooperates with the valve chamber 5^b to control the flow of fuel through the tube 4 in 120 the same way as in Fig. 1. In the illustration this form of my improvement is shown as being operated with illuminating gas, the tube 4 being connected with a source of such fuel through the medium of a pipe 4^b. It will of course be understood that the said 125 130

arrangement is equally well adapted for use in connection with vaporized liquid fuel as in Fig. 1 in which case a dish 27^a for holding the preheating fuel is also included in the structure and preferably supported on the fuel tube 4. In either case, when this form of my improved lamp is in operation the fuel passes through the tube 4 and out of the nozzle opening 4^a into the mixing tube 9^a air being drawn in through the tube 8^a and becoming mixed with the fuel in the same manner as in Fig. 1. The said mixture flows through the tube 9^a and the tube 9^c into the chamber 10^b from which it passes through the perforations 12^a to the mantle 27^b where it is ignited in the customary way. When the lamp is burning, the fuel in passing that part of the tube 4 which is surrounded by the mantle 27^b is heated and expanded to a maximum degree thus increasing its capacity for absorbing air to a maximum extent and resulting in perfect combustion at the mantle. This effect is still further assured by conducting the mixture itself through the mixing tube 9^a in close proximity to the mantle so that the mixture is delivered to the latter in a preheated condition and highly combustible state. In the form being described the tubular members 30 and baffle members 31 of the form of my improvement first described have been omitted from the air inlet tube 8^a although it is to be understood that these elements may be combined with said tube if found necessary or desirable.

In Figs. 8, 9 and 10 I have shown an arrangement for supporting the inverted mantle, somewhat different from that illustrated in Fig. 1. As shown in Fig. 9 a plate 24^a is secured in the shell 24 preferably at a point near its lower end and said shell is provided with a plurality of bayonet slots 18^a. These bayonet slots 18^a are adapted to receive the projections 19^a of a ring 19^b having a horizontal inwardly extending flange 19^c and adapted to substantially fit or lie against said plate 24^a when the projections 19^a are in operative position in the slots 18^a. The said flange 19^c is adapted to form a support for the projections 19 of the mantle ring 20 from which the mantle 21 is suspended as in Fig. 1. Rods 25^a extend downwardly from the ring 19^b and have their lower ends turned inwardly and connected with a tubular member 26^a whereby the latter is suspended at a distance below the mantle 21 in axial alignment with the aperture 21^a thereof as in the form of my improvement first described. In the arrangement being described when the parts are assembled the tubular member 26^a rests upon a projection 29^a formed on the tube 4 it being understood that the spring 29 of Fig. 1 may be introduced between said tubular member and projection as in said Fig. 1 if desired. The

form shown in Fig. 9 may also include a preheating dish 27^a which is secured to the tube 4 as in Fig. 7 in order to adapt this latter form for use with vaporized fluid fuel although it is to be understood that ordinary illuminating or other gas may be used as a fuel in which case the dish 27^a might be omitted. When it is desired to remove or insert the mantle 21 the shell 24 is raised, thus carrying the ring 19^b and mantle 21 with their associated parts along, the tubular member 26^a sliding along said tube 4 during this operation. When completely removed the shell 24 is inverted in which condition the projections 19 of the mantle which is to be removed rest upon the plate 24^a and support the mantle in an upright condition. The ring 19^b may now be disconnected from the shell 24 by rotating it relatively thereto to bring the projections 19^a opposite the open portions of the bayonet slots 18^a after which the old mantle is free to be lifted from the plate 24^a and a new one placed in position thereon. The ring 19^b is then placed over the new mantle and again connected with the shell 24 to lock the mantle ring in operative position after which the shell is returned to its upright position and with its parts again operatively connected with the lamp by sliding the tubular member 26^a along the tube 4 in a reverse direction. During this last named operation the said member 26^a serves to properly guide the aperture 21^a of the mantle over the tube 4 and prevents injury thereto in the same manner as in Fig. 1. In order to prevent an unintentional disengagement of the projections 19^a from the bayonet slots 19^b any suitable means may be provided as for instance the hook 22 shown in Fig. 8. This hook in its normal position closes one of the bayonet slots 18^a as illustrated and operates by gravity to and from said operative position as the shell 24 is manipulated in the same way as does the latch 23 of Fig. 1.

Fig. 11 illustrates a different form of air intake. In this form the shell 24^b is surrounded by a sleeve 24^c located at a distance therefrom to form an annular space 24^d and having an annular bead 24^e which forms an annular channel 24^f opposite to the inlet ends of the air inlet tube 8^c. The sleeve 24^c may be secured to the shell 24^b in any suitable manner as by means of a flange 24^g and rivets 24^h. When the lamp with the arrangement being described is in operation air is drawn into the space 24^d throughout the entire upper periphery of said shell 24^b and is conducted by the channel 24^f to the open ends of the air inlet tube 8^c through which it passes to the mixing tube as described hereinafter. In passing through the space 24^d the incoming air is preheated by contact with the shell 24^b and in this preheated condition is added

to the heated fuel thus bringing about a mixture having a maximum degree of combustibility. The sleeve 24^e by preventing a direct entrance of the air into the air inlet tube 8^e also prevents flickering of the light and provides in the channel 24^f a substantially constant supply of warm air for admixture with the fuel. The bead 24^e may be utilized as a means for supporting a proper shade or globe 24ⁱ if desired; when such shade or globe is in position only outside air can be drawn into the tube 8^e and no products of combustion are carried along because said shade is located between the flame of the lamp or the zone in which combustion is taking place and the upper end of the sleeve 24^e as is clearly apparent in Fig. 11. It will of course, be understood that the arrangement shown in Fig. 11 may if desired be included in the form of my invention shown in Figs. 1 and 8 in place of the structures illustrated therein. It will further be obvious that the preheating dish 27 of Fig. 1 instead of being carried by the tubular member 26 may be secured to the tube 4 as in Figs. 7 and 8 in which case the said member 26 will be independently supported by the rods 25 in the same way as in said Fig. 8.

30 In all the forms of my improvement the fuel of whatever character it may be is regenerated before it reaches the point of consumption and expanded to a maximum condition whereby it is capable of absorbing a maximum amount of oxygen and burns with a relatively perfect flame substantially free from carbon and consequently without smoke or the like. The flame is also extremely steady and does not flicker and results in an incandescent light of great brilliancy with a minimum consumption of fuel.

The arrangements are simple in construction and easy to operate and owing to the fact that the supply tube 4 extends through the mantle the lamps may be operated in the wind without causing a cooling of said tube 4 and without materially interfering with the efficiency of the lamp and when fluid fuel is used also does away with the danger of spluttering or other unintentional spreading of unvaporized fuel. The danger of fire caused by a defective operation of the lamp is thus obviated and the latter may in consequence be used with safety and without danger under all conditions either indoors or outdoors. The constructions also make the lamp particularly adapted for use in out of the way places where ordinarily illuminating means, except possibly of the most meager and unsatisfactory type, would not be available. When the lamp is to be extinguished the valve 6 is simply closed whereby the supply of fuel to the heated portions of the tube 4 is completely cut off and in the case of fluid fuel vaporization

thereof stopped almost immediately so that escaping gases or fumes due to partly consumed fuel are entirely avoided.

Various changes in the specific construction shown and described may be made within the scope of the claims without departing from the spirit of my invention.

I claim:

1. An incandescent lamp comprising a mixing tube, an air inlet tube in communication therewith, a mantle, means for supporting said mantle, a fuel conducting tube extending through said mantle into communication with said mixing tube and said air inlet tube and a downwardly flaring deflector within said mantle and surrounding said fuel conducting tube. 75

2. An incandescent lamp comprising a mixing tube, an air inlet tube in communication therewith, an outer tube surrounding said mixing tube at a distance, a mantle suspended below the one end of said outer tube, a fuel supply tube extending through said mantle into communication with said mixing tube and said air inlet tube, and means at the other end of said outer tube for deflecting the mixture of fuel and air from said mixing tube downwardly through the space between the latter and said outer tube whereby said mixture is conducted to the mantle 95 from above. 85

3. An incandescent lamp comprising a mixing tube, an air inlet tube in communication therewith, an outer tube surrounding said mixing tube at a distance, a mantle suspended at the lower end of said outer tube, a fuel supply tube extending through said mantle into communication with said mixing tube and said air inlet tube, means at the upper end of said outer tube for deflecting the mixture of fuel and air from said mixing tube through the space between the latter and said mixing tube to the mantle, a perforated ring located within the lower end of said outer tube and a downwardly flaring 105 deflector depending from said ring within the mantle and surrounding the fuel supply tube. 110

4. An incandescent lamp comprising a tubular shell, a mixing tube arranged concentrically within said shell, an outer tube located within said shell and surrounding said mixing tube at a distance therefrom, an air inlet tube extending through said shell and said outer tube into communication with said mixing tube, a tubular preheating means suspended from said shell at a distance below said mixing tube, a mantle suspended above said preheating means and having an aperture in axial alignment therewith, a fuel supply tube extending slidably through said preheating means and projecting through said mantle aperture into communication with said mixing tube and said air inlet tube, said preheating means serving to guide said 130

mantle aperture over said fuel supply tube as the latter is operatively connected with the mixing and air inlet tubes and a fuel receptacle connected with said fuel supply tube and forming a support whereby the latter is maintained in an upright position.

5. In an incandescent lamp, a supporting means provided with bayonet slots, a ring, a mantle connected with said ring, radial projections on said ring adapted to enter said bayonet slots whereby said mantle is operatively connected with said supporting means by means of a relative rotative movement of the mantle ring and a gravity latch 10 adapted to project across the horizontal portion of one of said bayonet slots whereby said ring is locked against rotation.

6. In an incandescent lamp a tubular shell provided with slots, a plate in said shell 20 above and in close proximity to said slots, a supporting ring adapted to lie against said plate, projections on said ring arranged to enter said slots whereby said supporting ring is removably supported on said shell, a mantle ring detachably clamped in position between said ring and said plate and a mantle connected with said mantle ring.

7. In an incandescent lamp a tubular shell provided with slots, a plate in said shell 30 above and in close proximity to said slots, a supporting ring adapted to lie against said plate, projections on said ring arranged to enter said slots whereby said supporting ring is supported on said shell, a mantle ring located between said ring and said plate, a mantle connected with said mantle ring and means for automatically locking said projections in said slots.

8. In an incandescent lamp a tubular shell 40 provided with slots, a plate in said shell above and in close proximity to said slots, a supporting ring adapted to lie against said plate, projections on said ring arranged to enter said slots whereby said supporting ring is supported on said shell, a mantle ring located between said ring and said plate, a mantle connected with said mantle ring, means for automatically locking said projections in said slots, a tubular guide member located at a distance from and in axial alignment with said supporting ring and rods connecting said guide member with said supporting ring.

9. In an incandescent lamp, a tubular 55 shell having diametrically opposite openings therein, an air inlet tube in said shell having its opposite ends in registry with said openings, and a sleeve located externally of said shell and at a distance therefrom and extending above said openings, 60 said sleeve being open above said openings

and closed at its lower end below said openings.

10. In an incandescent lamp, a tubular shell having diametrically opposite openings therein, an air inlet tube in said shell having its opposite ends in registry with said openings, and a sleeve located externally of said shell and at a distance therefrom and extending above said openings, 65 said sleeve being open above said openings and closed at its lower end below said openings, and having a circumferential groove formed therein in registry with said openings.

11. In an incandescent lamp, a device for mixing air and fuel, a mantle carried thereby, a preheating means, a fuel conducting tube having its exit end extending into the mixing device and forming therewith an 80 annular space about said exit end whereby the latter is exposed to the pre-heating flame and means for protecting said exit end of the fuel tube from the direct heat of the Bunsen flame.

12. In an incandescent lamp, a device for mixing air and fuel, a mantle carried thereby, a preheating means and a fuel conducting tube having its exit end extending 85 into said mixing device and forming therewith an annular space about said exit end into which the preheating flame extends.

13. In an incandescent lamp, a device for mixing air and fuel, a fuel conducting tube having its exit end extending into said mixing device and forming therewith an annular space about said exit end, a suspended mantle having an opening at its lower end through which said fuel tube extends and which forms an annular space about the 95 latter, and a preheating means located beneath said mantle, the flame from said preheating means passing freely through said mantle opening, along said fuel conducting tube and into the annular space about the 100 exit end thereof.

14. In an incandescent lamp, a device for mixing air and fuel, a fuel conducting tube connected therewith, and a suspended inverted mantle surrounding said fuel tube 110 and provided at its lower end with an opening through which said fuel tube extends and which forms a free annular space about said fuel tube.

In testimony whereof I have hereunto set 115 my hand in the presence of two subscribing witnesses.

OSCAR WIEDERHOLD.
